UNITED STATES PATENT OFFICE.

SIMON GREENFIELD, OF NEW YORK, N. Y.

FOUNTAIN-PEN.

1,300,379.

Specification of Letters Patent. Patented Apr. 15, 1919.

Application filed March 29, 1918. Serial No. 225,603.

To all whom it may concern:

Be it known that I, SIMON GREENFIELD, a citizen of the United States, residing at New York, in the county of New York and State 5 of New York, have invented new and useful Improvements in Fountain-Pens, of which the following is a specification.

The subject-matter of this invention is fountain pens, and the principal object of 10 the invention is to provide a fountain pen capable of holding two different colors of ink, of which a choice may be made when it is desired to write, and which is fed in such manner as to preclude any intermingling of 15 the inks.

Another object of the invention is the provision of a fountain pen of this character having its parts so arranged that valves or closures adapted to operate by gravity may 20 be incorporated in the feeding parts in such manner that when the barrel is inclined to write with one color, the flow of the second color will be automatically stopped.

With these objects in view and others, the 25 invention resides in the details of construction and in the arrangement and combination hereinafter described, defined in the claims, and shown in the accompanying drawings, forming a part of this specification, 30 it being understood the changes in the precise embodiment of the invention herein disclosed may be made within the scope of what is claimed without departing from the spirit of the invention.

35 In the accompanying drawings:—Figure 1 is an enlarged longitudinal sectional view through my improved fountain pen, the upper end of the barrel being broken away.

Fig. 2 is a cross sectional view, taken on 40 the line 2—2 of Fig. 1.

Fig. 3 is a similar view, taken on the line 3—3 of Fig. 1.

Fig. 4 is a still further enlarged fragmental sectional view, illustrating in particular the employment of means for controlling the flow of the ink in the pen-holding head.

Fig. 5 is a cross sectional view, taken on the line 5—5 of Fig. 4.

Fig. 6 is an enlarged fragmental sectional view, showing the employment of means for controlling the flow of the ink in the feeding plugs.

With more particular reference to the accompanying drawings, the numeral 15 denotes the barrel portion of the pen with

which is formed an interior concentric barrel 16, in order to provide the longitudinal concentric reservoirs 17 and 18 for holding the two different colors of ink. The lower 60 ends of these barrels are open, and their concentric end walls are screw-threaded, the outer barrel 15 being preferably interiorly screw-threaded, as at 19, while the inner barrel 16 is preferably exteriorly screw-threaded as at 20.

Threaded within the outer barrel 15 and upon the inner barrel 16, are the concentric annular flanges 21 and 22, respectively, integral with the pen-holding head 23, which 70 is formed with a cross partition 24 that serves as the end wall or closure for the said concentric reservoirs. As best seen in Fig. 3, this pen-holding head, below the said partition 24, is provided with two longitudinal 75 spaced-apart cavities 25 and 26, convexly shaped in back to back relation to conform with the customary shape of the stem ends of pen-points for receiving the same in back to back position. Transversely through the 80 cross partition 24, are provided the feed ducts 27 and 28, the former of which permits the ink to flow from the outer reservoir 17 into the cavity 25, while the latter provides a passage-way for the ink from the inner reservoir 18 to the other cavity 26.

Inserted in the said cavities 25 and 26 in back to back relation so that their nibs project in opposite directions, are the pen-points 29 and 30 together with their respective feeding plugs 31 and 32, which are of such size and form as to completely fill up said cavities liquid-tight, with the exception of small openings 33 and 34 extending longitudinally between the pen-stems and the 95 said plugs to provide suitable ducts through which the ink may pass to the underneath sides of the pen-points in the usual way. In Fig. 1, it will be noted that the integral wall 35, which separates the cavities 25 and 26, 100 serves as a means for holding the pens spaced from each other in back to back position so that the ink on one pen cannot intermingle with the ink on the other pen. In this figure, also, it will be seen that the pens 105 29 and 30 together with their plugs 31 and 32 are inserted in their respective cavities with their inner ends spaced from the cross partition 24 thereby forming ink chambers 36 and 37 in the upper ends of said cavities 110 through which the ink must pass before flowing into the ducts 33 and 34. In this

form of my invention, which does not include any valves or means for controlling positively the flow of the ink from the reservoirs to the pen-points, the relative rapidity 5 of the flow depends partly upon the character of the ink employed, although the flow may be controlled substantially by adjusting the positions of the pens and their plugs so as to increase or diminish the size of the 10 chambers 36 and 37. But for all general practical purposes where a pen supplying two colors of ink is needed, it will be found that, owing to the relatively small diameter of the ducts 33 and 34 in proportion to their 15 length, the ink will not flow so freely upon the upper pen as 30 as to drop from the nib thereof while the lower pen as 29 is being utilized in writing.

As a means of substantially cutting off 20 the flow of ink from the upper pen when it is desired to write with the lower one, I may provide, as shown in Fig. 4, the cross partition 24 with two transverse plugs 38, each provided longitudinally along one side 25 with a feed duct 39 to permit the passage of the ink as before. Intermediate its length each plug is also provided with a transverse circular opening 40 opening into the feed duct 39. Seated in each opening 30 40 is a ball valve 41, which is adapted to close communication through the feed duct 39, the wall of the duct 39 opposite the valve seat 40 being slightly cut away in arcuate form to accommodate a sector of the ball 35 in order to completely close communication. In this connection it should be noted that the seats 40 extend outwardly toward the circumference of the pen-holder from the said ducts 39, and that under this arrangement 40 when the lower pen, assuming it to be 29 as before, is held in position for writing, the ball controlling the feed therefor, will drop by gravity permitting the passage of the ink, while the ball operating in the 45 other plug, in dropping simultaneously, closes its duct against the passage of ink. Conversely, when the pen-holder is turned around with the position of the pens reversed, the ball valves, falling under the influence 50 of gravity, close the duct which feeds the pen 29 and opens the duct for feeding the now lower pen 30.

Instead of seating the ball valves in the cross partition 24, I may provide as best 55 shown in Fig. 6, the feeding plugs 31 and 32, preferably near their lower ends, with openings or seats as 42, in communication, each with its respective feed duct as 33 and 34. In each opening is seated a ball valve 41 60 as before, the same being adapted to close or open its feeding duct accordingly as the pen fed thereby is above or below. When it is contemplated using ink of a poor character in the fountain pen, this last method 65 of controlling the flow of the ink is pre-

ferred, since in the upper pen the flow of the ink is positively stopped immediately above the pen-point.

Having thus described my invention, what I claim is:—

1. In a fountain pen capable of employing two colors of ink, concentric barrels spaced-apart to provide an inner and an outer longitudinal reservoir, a holding head formed with concentric flanges removably connected respectively with said concentric barrels and having individual ink ducts for said reservoirs, feeding plugs arranged in said head longitudinally thereof to individually receive and convey the ink from said ink ducts, and means combined with said holding head and said feeding plugs to receive and write with either color of ink without one color intermingling with the other. 75

2. In a fountain pen construction, the 80 combination of concentric barrels formed spacedly to provide two concentric longitudinal ink reservoirs, a pen-holding head formed with concentric flanges removably connected respectively with said concentric barrels, individual ink ducts in said head, and means combined with said head including separated writing nibs for individually receiving the ink from said ink ducts. 85

3. In a fountain pen construction, the 90 combination of concentric barrels formed spacedly to provide two concentric longitudinal ink reservoirs, a penholding head formed with concentric flanges removably connected respectively with said concentric barrels, individual ink ducts in said head, means for controlling the flow of ink through said ducts, and means combined with said head including separated writing nibs for individually receiving the ink from 100 said ink ducts. 105

4. In a fountain pen capable of employing two colors of ink, concentric barrels spaced apart to provide two concentric longitudinal ink reservoirs, a pen-holding head formed with concentric flanges removably connected respectively with said concentric barrels and provided with a cross partition comprising an end closure for said barrels, said partition having independent 110 ink ducts therethrough one for each reservoir, valve means seated in said partition and operated under the influence of gravity to open and close the ink ducts, said head having independent cavities one for each 120 feeding duct to open into, and means engaged in said cavities to direct the ink therefrom without intermingling to separated writing nibs. 115

5. In a fountain pen capable of employing two colors of ink, barrels formed spaced apart to provide two concentric longitudinal ink reservoirs, a pen - holding head formed with concentric flanges removably connected respectively with said concentric 125 barrels. 130

barrels and having a cross partition comprising an end closure for said barrels, said partition having independent ink ducts therethrough one for each reservoir; said 5 head having independent cavities therein one for each feeding duct to open into, a feeding plug engaged in each cavity to receive and conduct the ink, a valve device

combined with each feeding plug to control the flow of the ink, and means including separated oppositely disposed writing nibs whereby to write with the ink supplied through either feeding plug. 10

In testimony whereof, I have signed my name to this specification.

SIMON GREENFIELD.
